ABSTRACT OF THE DISCLOSURE

An apparatus and method which enable patterns to be embossed by inflating means in successive portions of a material web. The embossing operation is facilitated by a communicating passage which is pressed out in the web portion immediately following the web portion being embossed, so that when said two portions are separated and opening is exposed in the said following portion, for the nozzle of said inflating means.

BACKGROUND

The present invention relates to a method for embossing repeated patterns in strip material, preferably metal strip, at suitable temperatures, at least two material webs in superimposed relationship being advanced intermittently and subjected therebetween to the action of a pressure medium, in predetermined zones during the repeated stoppages of the web material, the said pressure medium pressing out the desired pattern in relief, whereupon the work piece on which the pattern has been embossed is separated and the working sequence repeated.

It is previously known to emboss patterns in web or sheet-like material by means of a pressure medium, usually oil or air, whereby substantially the same result is obtained as when embossing by means of mechanical sheet-metal presses. The method has gained particular interest in the embossing of repeated patterns in mass produced articles made from metal strip or metal plate, e.g. heat exchangers. The usual practice is to arrange a number of material webs, normally two, in superimposed relationship and inject the pressure medium between the webs so that certain predetermined zones, forming a pattern, are distended in either of the two webs or in both of said webs. The embossing operation is effected intermittently for each pattern, by forcing the webs apart at some suitable point along the edges of the same and injecting the pressure medium between the webs at this point. The pressure medium forces its way through flow paths which have been previously disposed between the webs, and presses out relief patterns in the walls along said path, while remaining zones of the said webs are sealed off from one another and prevent the pressure medium from entering therein. Normally only one pattern is embossed at a time, it being necessary to cut-off the supply of pressure medium to the following portions of the continuous webs, a procedure which is effected by means of so-called holder plates which clamp the webs together at some suitable point in the direction of feed, behind the embossing zone. The pressure is relieved after each embossing operation, whereupon the embossed zone of the web is severed transversely of the webs, and removed so as to prepare a place for the intermittently advanced web so that the next pattern can be embossed. However, before the next pattern can be embossed, an opening must be made manually between the two webs.

2

This latter operation constitutes the true obstacle in providing for a rapid and continuous embossing sequence and consequently it is the object of the invention to eliminate this disadvantage.

In accordance herewith, the invention is mainly characterized in that a passage communicating with the adjacent, unembossed portion of the web is formed in conjunction with the step of embossing a pattern on the preceding web portion, and that each embossed web portion is separated from the web material, the communicating passage being parted in conjunction therewith so that an opening is formed in the adjacent web portion, after which the source of pressure medium is connected to the said opening.

The invention also includes an arrangement for carrying out the method, which is mainly characterized by a delay station wherein a determined portion of the advanced material web is periodically stopped so that it can be embossed in conformity with the desired pattern, the said station being designed with two opposing surfaces which restrict the extent to which the material is distended and the shape of the embossed pattern, and by holder means which are capable of being urged against the webs and which, at least during the embossing operation, close the pressure-medium communicating passage, leading to said adjacent unembossed portion of the web, and by cutting means movably arranged in front of said station and intended to cut embossed, finished portions of the web from the portion of the web located at that moment in the station, said means cutting along a line which crosses the communication passage at a desired position between the ends thereof so that an opening is formed in the portion of the web located in the station, the cut, finished web portions being removed and a nozzle capable of being connected to a source of pressure medium being movable into and out of sealing engagement with said opening.

The invention will be described in greater detail below with reference to a number of embodiments shown diagrammatically in the accompanying drawing, further characterizing features of the invention being disclosed in conjunction therewith.

DETAILED DESCRIPTION OF INVENTION

FIGURE 1 shows in perspective a diagrammatical view of a machine for carrying out the method according to the invention, the said machine having been provided with essential means for effecting a continuous, semi- or fully automatic embossing operation when intermittently advancing, for instance, two metal webs of which one is freely arranged upon the other.

FIGURE 2 shows a cross section of an embodiment of an arrangement, included in the machine, to restrict the extent to which the pattern is distended, as well as a holder plate intended to cut off the supply of pressure medium to the portions of the webs not being embossed.

FIGURE 3 shows a section of a modified embodiment of the arrangement according to FIGURE 2.

FIGURE 4 shows a further modification of the arrangement shown in FIGURES 2 and 3.

FIGURE 5 shows in perspective, by way of an example, a gas burner for separating the embossed portion of the web.

FIGURE 6 shows, in perspective, a view of a modified arrangement, in the form of shears for clipping off the embossed portion of the web.

FIGURE 7 shows diagrammatically a type of screw nozzle adapted to be inserted into an inlet opening formed in the next portion of the web to be embossed subsequent to its being advanced into the delay station, said inlet opening being formed in conjunction with the embossing of the pattern in the preceding portion of the web.

FIGURE 8 shows another alternative of an insertion nozzle, intended for the same purpose as the nozzle according to FIGURE 7 and provided with a sealing means.

FIGURE 9 shows a simplified form of a similar nozzle not provided with special sealing means.

FIGURE 10 shows diagrammatically and in perspective a machine which substantially coincides with the machine shown in FIGURE 1 but which is somewhat modified for the purpose of working with webs of material which have been previously provided therebetween with the outlines of the pattern to be embossed and joined together.

FIGURE 1 shows a supporting member 1 on which are rotatably mounted two shafts 3 and 4 each supporting a roll of strips 5 and 6, comprised of metal, plastic or the like. Positioned in front of the support 1 is a further supporting member 7 presenting two vertical posts 8 and 9, of which the first mentioned post 8 is suitably displaceable towards and away from the post 9 and capable of being locked in an adjusted position, so that the distance between the two posts can be set in accordance with the width of the material coiled on the drums 5 and 6. However, there is nothing to prevent the two posts from being stationary and arranged at a fixed distance apart.

The posts 8 and 9 also form bearing supports for a feeder mechanism which, in the illustrated example, has two driven rolls 10 and 11 and a backing roll 11a disposed beneath rolls 10 and 11. The rolls 10, 11 and 11a are driven, via a gear 13 and shafts 14, 15 extending therefrom, by an electric motor 12. The motor is adapted to be driven intermittently; this may be effected automatically by programming.

As can be seen from the figure the webs 16 and 17 are uncoiled from the coils 5 and 6 and passed together, freely positioned one on top of the other, between the guide posts 8 and 9 and between firstly the roll 11a and secondly the two rolls 10 and 11 into an apparatus which is positioned in front of the rolls and in which the web material is embossed according to the invention.

The apparatus mainly comprises an elevatable die 18 provided with a centrally positioned upwardly projecting support surface 19 on which determined lengths of the intermittently advanced webs 16 and 17 are periodically stopped, to permit the embossing operation according to the invention to be carried out. Located above the die 18 is a stationary solid block 20, provided with a recessed backing surface at 21. The shoulder 22 formed on each side of the block 20 projects down at the side of the support surface 19 which can be made to abut direct against the backing surface 21, or alternatively be stopped or fixed at a determined distance from the same. This can be effected, for instance, by means of distance pieces inserted between the surfaces, or by means of lugs or shoulders projecting out from one or the other of the surfaces or from them both.

Since according to the invention, it is intended to utilize the two surfaces as a means for restricting the extent to which the material is the relevant web portion or portions 16, 17 to be embossed is distended, several alternative designs in the structure of the two surfaces 19 and 21 may be applicable. Thus, in the simplest construction it may be the intention to emboss the portions of the web located in the described apparatus so that together they obtain a form which may be compared with the outer contours of a cushion. In this instance the one surface 19 or 21, for example, may be provided with a continuous rectangular strip, projecting out from said surface and which is pressed into contact with the webs 16 and 17, against the reaction of the other surface. Upon ejecting a pressure medium in between the portions of the web which have been mechanically pressed together in the manner described, the one web portion is urged against the opposing backing or support plane, whereas the second web portion abuts its own support surface and cannot be distended. This means that only the one web portion will be embossed. The edge of the above mentioned strip thus defines

the outer contour of the embossed pattern while at the same time holds the webs sealingly compressed against each other along its pressure plane, so that the pressure medium can only act within the confines of the strip.

5 Naturally the strip-frame can be modified to suit the configuration of any required pattern. Further, several strips may be arranged on the support or backing surface for the purpose of providing a pattern and for sealing the web portions, in the manner disclosed above.

10 If, on the other hand, it is desired to emboss both portions of the web it is possible to arrange complementary strips of congruent shape on both surfaces, the two web portions being sealingly compressed together by the strips while situated at a distance from their respective reaction surfaces, and urged into abutment with the latter by the pressure medium

15 According to another alternative one or the other, or both of the two surfaces may be engraved, as shown with double dotted lines 23 in FIGURE 1, the reaction planes, 20 prior to the embossing operation, being compressed together with the portions of the web lying therebetween. On commencing the embossing operation the material of the web portions is only pressed out at those positions where the engraving is located, and distends to form the 25 pattern.

20 In this connection there are two important requirements which must be fulfilled to enable the embossing operation to be confined to those particular web portions which are at that instance located in the described apparatus. Thus, 30 the possibility must be found of closing the path of the pressure medium to subsequent portions of the webs and an inlet path for the pressure medium must be provided, leading to the zones in the web portions fed into the apparatus, to be embossed. The first requirement can be 35 fulfilled by using a simple holder device, extending transversely across the webs. This may be a separate device which may also be separately operated, or may comprise a strip-like shoulder located on one or both of said surfaces, 19, 21.

40 In fulfilling the second requirement an inlet channel for the pressure medium can be defined by strips positioned on the backing and support surfaces, or alternatively one or both of the said surfaces may be engraved so that the web portions can be parted at this point and the pressure 45 medium nozzle inserted.

To illustrate the aforementioned, reference is made to FIGURES 2 to 4 which comprise sections of alternative embodiments of the two surfaces 19, 21, taken in the direction in which the webs are advanced.

50 FIGURE 2 can be said to illustrate the instance where the two web portions 16a and 17a, one superimposed on the other, are to be distended between the die 18 and the block 20 to form a cushion-like object, the web portions being held in certain spaced relationship leaving a gap 24 55 which is later filled when the pressure medium is injected between the web portions, via the inlet opening 25 formed during the preceding embossing operation. In this instance the distance between the two surfaces is maintained by the two shoulders or strips 25a and 26, located on said surfaces. The shoulders or strips form, at the same time, holder members which prevent the pressure medium from continuing backwards past the same, i.e. in the opposite direction to which the webs are being advanced.

55 On the other hand the section according to FIGURE 2 can be said to represent alternatively the instance where the two surfaces 19, 21 are each provided with upwardly projecting, patterning strips of complementary configuration.

70 FIGURE 3 shows the alternative in which the backing surface 21 is provided with a tortuous engraving 27, whereas the opposing support surface 19 is completely smooth. In this instance the two plane surfaces of the members 19, 21 can be used as holder plates, since on being urged against the portions of webs 16a and 17a 75 lying therebetween they compress said web portions seal-

ingly over their entire surface, with the exception of the locations in which the said surfaces have been engraved.

FIGURE 4 shows the alternative in which the two surfaces 19 and 21 are provided with complementary engravings 28 and 27 respectively, whereby the two web portions 16a and 17a are distended into the respective engravings and provided with embossed patterns.

Returning to the description of FIGURE 1 the first block 20 rests on an underlying plate or slab 29 through the intermediary of four posts 30, positioned in the four corners of said plate (only two posts being shown in the figure). The posts 30 serve, at the same time, as guides for the vertically movable block 18, which is in turn supported by a hydraulic piston 31 operated from a hydraulic cylinder 32 which is supplied with hydraulic pressure medium via a delivery conduit 33. Thus, through the intermediary of these arrangements the block 18 can be made to coact with the block 20, for the purpose of carrying out some of the alternative functions, described very generally above, in conjunction with embossing a pattern, in the described apparatus. Further, in accordance with the invention arrangements are preferably incorporated which permit programming of the movements of the block 18 in conjunction with the intermittent advancing movement of the webs.

FIGURE 1 illustrates a stage in the process wherein a double-layer web portion 35, in which a tortuous pattern has been embossed, has been advanced away from the surfaces 19, 21 on a roller belt 36, at the same time as a new, double-layer web portion has been moved into the position previously occupied by the preceding portion, i.e. between the surfaces 19 and 21, and securely clamped therebetween.

As can be seen from the figure a communicating passage 37, in accordance with the most important novel feature of the invention, extends rearwards up to the edge of the clamped surfaces 19, 21 and terminates within the following web portion at that point where pressure medium will later be injected for the purpose of embossing the pattern 23 in the said double-layer web portion situated between the two surfaces 19 and 21.

Before the next portion of the web can be embossed, the embossed web portion 35 must be severed from the web and, for instance, placed on stack 38 of finished articles, so that the inlet opening 39 formed during the preceding embossing operation and leading to the pattern 23 can be reached and the source of pressure medium connected thereto. In previously known methods of embossing strip material, in which no communication passage according to the above has been formed, the leading web portion, e.g. the portion indicated by the reference numeral 35, has been cut off transversely to the longitudinal direction of the web without leaving an embossed portion. Consequently before connecting up the source of pressure medium it has been necessary to force apart the compressed webs in order to obtain an opening leading, for instance, to the portion, 23 to be embossed. This task is both difficult and time consuming, requires skilled manual effort and, last but not least, constitutes a definite obstruction to automatizing the whole process.

The general object of the invention is thus to eliminate this obstruction and to enable the process to be made fully automatic.

The problem is solved according to the invention in that the embossed communication passage 37 is parted at a convenient point between its ends. Consequently an opening is automatically obtained, into which a nozzle for the pressure medium can be inserted without it being necessary to create said opening manually. In this way it is also possible to coordinate the separating and embossing operation in automatic coordination, which increases the precision and accelerates the production rate.

In the example shown in FIGURE 1, a circular saw 40 is used to part the communication passage; the saw being mounted on a beam 41 which is guided for move-

ment by two guides 42 and 43 positioned in a frame 44. The circular saw 40 is driven via a suitable form of transmission means (not shown) by an electric motor 45 resting on a support bracket 46 attached to the beam 41. Further, positioned above the guide 42 is a double-action pressure piston arrangement 47, the projecting piston rod 48 of which is connected, via a coupling 49, with the beam 41. The said beam can thus be driven with reciprocatory movement so that the circular saw 40 cuts through the discharged web portions and parts the finished article from the remainder of the web along a line passing through the communication passage 37.

In this way an opening is exposed at point 39, in accordance with the above, into which a pressure medium nozzle can be inserted.

An example of how this can be used is illustrated in FIGURE 1, in which the reference numeral 50 indicates a stationary bracket which at its upper end pivotally supports a support arm 51. The support arm is pivoted by means of a double action type pressure piston arrangement 52, the piston rod 53 of which is pivotally connected at 54 with the arm 51. Further, the free end of the arm is provided with a rearwardly directed pressure medium nozzle 55, which is connected via a pressure line 56, to a pressure medium source (not shown). The dimensions and positioning of the pivot arm 51 are so calculated that the nozzle 55 "feels" its way into the opened passage between the webs, at the opening 39, when the arm swings downwards. In normal events an immovable nozzle provides sufficient sealing in itself, against the walls of said opening when the pressure medium is caused to flow from the nozzle into the opening. In certain cases, however, it is expedient to turn the nozzle within the opening, during its penetration therein. The nozzle 55 in FIGURE 1 is, for this purpose, rotatably mounted on the arm 51 and can be turned by means of, for instance, a chain 57 driven by an electric motor 58, secured on the arm 51. The motor is suitably of the reversible type so that the nozzle can be turned in either direction. In this connection it can be mentioned that the connection between the nozzle and the source of pressure medium is suitably program controlled relative to remaining functions of the process.

FIGURE 5 shows an alternative to the cutting means according to FIGURE 1, comprising a cutting torch 59 intended to replace the saw 40, in FIGURE 1. As can be seen from FIGURE 5 the flame 60 cuts the webs along a transversal line 61, cutting the communication passage 37 in such a way that an opening is left at the next, unembossed web portion is left at 62.

Another alternative cutting means is shown in FIGURE 6, said means comprising a shearing device having a lower, suitably stationary blade 63 and an upper movable blade 64. To avoid buckling in the communicating passage when cutting the web, a sharp cutting point 65 is arranged on the upper blade, the said point 65 being so positioned that it only comes into contact with the communicating passage 37 during the cutting process.

FIGURES 7 to 9 show a few alternative designs of the pressure medium nozzle 55 in FIGURE 1.

FIGURE 7 illustrates once again the pressure medium conduit 56 and the nozzle 55, which is mounted for rotation on the arm 51, the movement of said nozzle being produced by a chain wheel 66 driven by the chain 57, shown in FIGURE 1, in either direction. The tip 67 of the nozzle itself is provided with a screw thread type sealing flange 68 intended to sealingly close the nozzle, during rotation, to the inner walls of the exposed opening between the webs.

Another example of a nozzle is shown in FIGURE 8, wherein the body 55 of the nozzle is unrotatably mounted and provided with a conical nozzle tip 69, around the base of which is positioned a gasket 70 intended to be urged sealingly against the edge of said opening during passage of the pressure medium therethrough.

FIGURE 9 shows substantially the same arrangement as FIGURE 8 with the exception that the gasket 70 has been omitted. The shoulder 71 forms the necessary sealing means, and replaces the gasket means.

The foregoing has been confined to a method in which the webs are placed loosely one on top of the other and, in this state, operated in accordance with the invention. In many cases, however, it may be desirable to join the two webs intimately together. This can be effected in a variety of ways. Thus during the process the webs can be bonded together by means of an adhesive or a cement. Further, heat may be supplied to the web by means of electric windings disposed in the blocks 18 and 20, whereby the abutting surfaces of the webs, if for instance they are made of plastic, can be fused together. In the case of metal webs, for instance, the two webs may be welded together. Further, it is also possible to coat the facing surfaces of the webs with solder, e.g. tin, and join them together by a soldering process.

According to a final alternative the process can be effected without joining the webs together, the severed portions of the webs, loosely positioned one on top of the other, remaining in free superimposed relationship after the embossing process has been carried out. The loose portions of the webs may, however, be joined together later, using methods suitable for the purpose.

In this connection it may be mentioned that a method has previously been suggested wherein double-layer web material has been prepared beforehand by rolling together two metal webs. In this method, however, at least one web has been pre-patterned using a stop weld substance, which prevents the webs from being welded together during the rolling process at the positions treated with stop weld substance. The process according to the invention, however, can also be applied in this case.

To illustrate the differences which occur when carrying out the process with webs which have been joined together from the outset, reference is made to FIGURE 10 which to a very large extent corresponds with FIGURE 1. FIGURE 10, however, shows only one reel on which is coiled two metal webs previously welded together by rolling, between which webs a coating of material has been applied in a continuous pattern along the inner faces of the webs, the said material preventing the surfaces thus treated from being welded together during the rolling process. This obviates the necessity of arranging holder means on the blocks 18 and 20 around the pattern when embossing. On the other hand it is important in this context that the blocks are capable of being adjusted to a determined distance between the two surfaces 19 and 21 so that the extent to which the pattern 73 is distended upwards can be regulated by the same. Since, in this case it is not necessary to use engraved reaction surfaces or strips as in the case of the arrangement according to FIGURE 1, the pressure medium must be prevented in some other way from flowing back towards the reel 72 and embossing the continuous, pre-arranged pattern 74 located behind the blocks 18 and 20. A simple solution to this problem is the use, in accordance with FIGURE 10, of a separate holder means 75 suitably supported by a piston rod 76 projecting from a stationary pressure piston arrangement 77. By urging said holder means 75 down against the webs prior to the embossing operation, and against an abutment means 78 positioned under said webs, it is possible to stop effectively the flow of pressure medium from the communication passage 79 back to the pattern 74. Embossing of the pattern 34 and forming of the communicating passage, as well as severing of the finished web portion can be effected in the same way as with the arrangement according to FIGURE 1.

The method according to the invention can be adapted with cold working as well as with hot working of the webs.

Although the invention has been described with reference to a substantially stationary apparatus, the material

web being moved through the apparatus, it is also possible to arrange for the material web to be stationary and the working apparatus to be moved stepwise along the same.

According to one alternative of the invention it is possible to work with more than two plates on top of each other and furthermore, with several different patterns side by side; the webs then being divided up along their length.

The invention is not restricted to the illustrated and described embodiment of the same but can be varied within the scope of the following claims.

What is claimed is:

1. A method for embossing repeated patterns in strip material formed from at least two superimposed material webs, said method comprising intermittently advancing said strip material through an embossing zone, injecting a pressure medium between predetermined regions of adjacent webs in said embossing zone to cause the webs to be deformed in said regions and become embossed, periodically cutting the strip material after it has passed through said embossing zone and has undergone an embossing operation, said strip material being cut to leave a portion thereof extending from said embossing zone such that the embossed regions of the already embossed strip material each provide a communication passage extending to the regions of the strip material which is next to be embossed, said pressure medium being injected to the latter regions of the strip material to be embossed via each said communicating passage.

2. A method as claimed in claim 1 wherein each communication passage is closed to the following webs about to enter the embossing zone for at least the length of time which the preceding webs are kept under pressure in said embossing zone.

3. A method as claimed in claim 1 comprising retaining the webs to be embossed in said embossing zone between two flat support surfaces in determined space relationship adapted to restrict the extent to which the webs are deformed by the distance between said surfaces.

4. A method as claimed in claim 3 comprising varying the distance between the support surfaces to regulate the extent to which a pattern is formed by said predetermined regions.

5. A method as claimed in claim 1 comprising retaining the portion of the webs to be embossed between two support surfaces capable of being urged towards each other, at least one surface being engraved in such a way that the web is forced by the pressure into the engraving and substantially conforms to the walls of the same.

6. A method as claimed in claim 5 wherein the support surfaces and the strip material are moved relative to each other.

7. A method of claimed in claim 2 wherein each communicating passage is closed by applying a press die tool to the end of the passage.

8. A method of claimed in claim 1 wherein the cutting of the strip material is effected transversely of the strip material.

9. A method as claimed in claim 1 wherein the injection of the pressure medium into the predetermined regions of adjacent webs is effected by introducing a nozzle into each communication passage of the already embossed strip material and passing the pressure medium to each nozzle.

10. A method as claimed in claim 1 wherein a portion of the strip material is intermittently fed between support surfaces and permitted to remain there during the embossing operation in said embossing zone while the injecting and cutting of the material is effected in synchronism with the intermittent advancement of the material web.

11. A method as claimed in claim 1 wherein the webs of the strip material are arranged loosely in superimposed relation, the method further comprising pressing the webs

together in the regions not to be embossed prior to the injection of the pressure medium into said predetermined regions which are to be embossed, and interrupting communication between the regions to be embossed in the strip material in said embossing zone and the subsequent strip material which has not yet entered the embossing zone.

12. A method as claimed in claim 1 wherein the webs of the strip material are arranged in superimposed relationship and are bonded together, the method further comprising interrupting communication between the regions to be embossed in the strip material in said embossing zone and the subsequent strip material which has not yet entered the embossing zone.

13. Apparatus for embossing repeated patterns in strip material constituted by at least two superimposed material webs, said apparatus comprising means for advancing the strip material intermittently through an embossing zone, means for injecting a pressure medium, into predetermined regions of said strip material during repeated stoppages thereof in said embossing zone, mold means at said zone for forming a desired pattern in relief on said strip material in said regions in which the pressure medium is injected, means for separating embossed blanks from said strip material after the latter has passed through said embossing zone, the latter means being positioned to separate the blanks and leave a portion of the embossed material attached to the strip material in said embossing zone awaiting embossing, whereby each embossed region in said embossed portion provides a passageway extending to a corresponding region of the strip material in said zone awaiting embossing, said means for injecting pressure medium to said predetermined regions of the strip material in said embossing zone comprising a nozzle associated with each embossed region of the embossed portion of the strip material for supplying pressure medium thereto and thereby to said strip material in the embossing zone via the associated passageway and means for interrupting flow of pressure medium from said strip material in said embossing zone to the strip material which is next to be introduced into said embossing zone.

14. Apparatus as claimed in claim 13 wherein said mold means comprises members having opposed spaced

surfaces between which the strip material is passed, said surfaces having a groove pattern formed therein for restricting the magnitude and extent of deformation of the webs in said predetermined regions in which they are embossed.

15. Apparatus as claimed in claim 14 wherein said opposed surfaces have partly flat support surfaces and partly shaped strips projecting outwards from at least one support surface.

16. Apparatus as claimed in claim 14 wherein said opposed surfaces have partly flat support surfaces and engraving portions disposed in at least one support surface and forming said grooves.

17. A apparatus as claimed in claim 14 wherein said opposed surfaces have flat support surfaces, the distance between which are capable of being adjusted.

18. Apparatus as claimed in claim 13 wherein said means for interrupting flow of pressure medium comprises holder means including shoulders protuding from at least one support surface to clamp the webs sealingly against reaction surfaces.

19. Apparatus as claimed in claim 19 where said holder means comprises separately arranged and operable clamping jaws.
